CLAIM

We claim the ornamental design for a lotion pump head, as shown and described.

DESCRIPTION

FIG. 1 is a perspective view of an ornamental design for a lotion pump head;

FIG. 2 is a front elevation view of the lotion pump head of FIG. 1;

FIG. 3 is a rear elevation view of the lotion pump head of FIG. 1;

FIG. 4 is a right side elevation view of the lotion pump head of FIG. 1, the left side elevation view being a mirror image thereof; and,

FIG. 5 is a top plan view of the lotion pump head of FIG. 1.
